UNITED STATES PATENT OFFICE.

THOMAS C. PEARS, OF PITTSBURG, PENNSYLVANIA.

DESIGN FOR GLASSWARE.

Specification forming part of Design No. 7,256, dated March 24, 1874; application filed December 13, 1873.
[Term of Patent 7 years.]

To all whom it may concern:

Be it known that I, THOMAS C. PEARS, of Pittsburgh, in the county of Allegheny and State of Pennsylvania, have invented a new and useful Improvement in Design for Glassware; and I do hereby declare the following to be a full, clear, and exact description thereof, reference being had to the accompanying drawing forming a part of this specification, in which—

Figure 1 represents my improved design upon a goblet, and Fig. 2 shows the same upon a bowl.

My design consists in the alternate arrangement of a plain flute and a group of two or more prismatic or concave flutes upon the outer surface of goblets and other articles of glassware,

To enable others skilled in the art to make and use my improvement, I will describe it.

On the outer surface of goblets, bowls, and other dishes composing the set, I arrange alternately a plain flute, *a*, and a group of two or more prismatic or concave finger flutes, *b*. These flutes extend from the base of the bowl about two-thirds of the way up; above that the article is made plain.

What I claim as my invention, and desire to secure by Letters Patent, is—

The design for glassware consisting of an alternate arrangement of a plain flute and a group of two or more finger flutes upon the outer surface of the same, as shown and described.

In testimony whereof I, the said THOMAS C. PEARS, have hereunto set my hand.

THOS. C. PEARS.
